AMUSEMENT DEVICE

Ambrose W. Groh, Cincinnati, Ohio

Application August 31, 1948, Serial No. 47,120

8 Claims. (Cl. 272—4)

1

This invention relates to an amusement device and more particularly to a device for use with racing turtles.

In recent years the sport of turtle racing has become increasingly popular because of the fact that, as distinguished from other animal races, a turtle race can be, and indeed must be, confined to a relatively short track so that the sport may be conducted indoors. Further, the unpredictability of a turtle's movements cause such races to be much more entertaining than races between other types of animals which will run at a more or less constant speed.

Since the turtles are relatively small, and the race track relatively short, devices for turtle racing in the past have only permitted the races to be observed by a relatively small number of spectators. Furthermore, some difficulty has been encountered in the sport of turtle racing in causing all the turtles in the race to start running substantially at the same instant.

With the foregoing considerations in mind it is an object of the present invention to provide a race track and starting gate for turtle races which will enable a race to be viewed by a large number of people, and which will insure all of the turtles in the race commencing their run at substantially the same time.

The above and other objects of the invention which will be pointed out hereinafter, or which will become apparent as the description proceeds, are accomplished by that certain construction and arrangement of parts of which the following description sets forth an exemplary embodiment.

Reference is made to the drawings forming a part hereof and in which:

Figure 1 is a plan view of one form of the device.

Figure 2 is a front elevational view of the same.

Figure 3 is a cross-sectional view taken on the line 3—3 of Figure 2.

Figure 4 is a fragmentary view of a modified form of the device, and

Figure 5 is a fragmentary cross-sectional view taken on the line 5—5 of Figure 4.

Briefly, in the practice of my invention a plurality of substantially horizontal trackways are provided at different elevations. These trackways may be in stepped relation as in the embodiment of Figures 1 to 3 inclusive, or they may be directly superposed as in the embodiment of Figures 4 and 5.

The trackways are generally of channel shape so as to confine the movement of the turtle to a well defined path. Communicating with each of the trackways is a trackway which is inclined at

2

a steep enough angle so that the turtle placed thereon will slide down, and each of the inclined trackways is provided with a starting gate or baffle to hold the turtle against sliding down the inclined trackway. All of the baffles or gates are connected for simultaneous actuation, so that by a single movement all the turtles are released so that they slide down the inclined trackways on to the horizontal trackways. The slight bump they sustain upon contact with the horizontal trackways causes them to commence their travel therealong.

Referring now to the drawings and describing first the embodiment of Figures 1 to 3 inclusive, there is shown a stepped configuration which may comprise a piece of sheet metal suitably formed on a press brake to provide in effect a plurality of treads 10 which constitute the floors of the respective trackways, and a plurality of risers 11, which constitute one of the side gates for the respective trackways. To prevent the turtles from falling off one trackway on to the one the next step below, and to constitute the other side guide, there is provided for each trackway a transparent plate 12 which may be of glass, transparent plastic or similar material. The plates 12 are held in place by means of the clips 13 which are secured to the respective risers 11. Thus, a turtle running along in trackway 10 is confined to the trackway by the riser 11 on one side, and by the transparent plate 12 on the other. By virtue of the transparency of the plates 12, the turtles on the various tracks may be viewed without hindrance from the front of the device, as seen in Figure 2, or from the left as seen in Figure 3. The device thus far described may be mounted upon any convenient framework, indicated generally at 14. At the finish ends of the trackways there is provided a barrier 15 to prevent the turtles from falling off the ends of the trackways.

At the starting ends of the tracks there are provided the inclined trackways 16 which are also of stepped configuration and which are separated by the risers 17, and which may also, if desired, be provided with transparent sides, although this is not particularly necessary.

Pivotedly mounted in brackets 18 is an inclined rod 19, on which are rigidly mounted the gate elements, or baffles, 20, one extending into each inclined trackway 16.

In use, with the gate elements 20 in the position shown in the drawings, the turtles are placed in the respective inclined trackway 16 above the gate elements 20. When the race is to be started the rod 19 is simply rotated to raise the gate ele-

ments 20, whereupon the turtles slide down the respective inclined trackway 16 on to the horizontal trackways 10, so that incident to the slight bump they sustain upon contact with the trackways 10, they will start their travel along the horizontal trackways.

The inclined trackway may be secured to the horizontal trackway assembly in any suitable manner, as by means of the bracket 21, as well as by riveting, welding, or the like.

The embodiment of Figures 4 and 5 is similar to that of Figures 1 to 3 inclusive, except that here the trackways are disposed one directly above the other. Thus the trackways may comprise the channel members 10a to each side of which may be secured a transparent plate 12a as by means of the brackets 13a. The various trackways 10a may be welded or otherwise secured to the upright rods 22. The inclined trackways 16a may be secured to the horizontal trackways 10a in any desired manner and in this instance have been shown as having the transparent side baffles or risers 17a which act as side guides for the inclined trackways.

In this embodiment the various gate elements 20a are rigidly mounted on the rods 19a, which are pivotally mounted in the risers 17a, and which also carry fixed thereto the crank elements 24 which in turn are pivoted to the actuating link 25. It will be clear that upon downward movement of the link 25, all of the gate elements 20a will swing upwardly simultaneously.

It will be clear that the general principles of the two embodiments are the same and that both embodiments have the advantages outlined above, although they differ in specific details. It will also be clear that numerous modifications may be made without departing from the spirit of the invention. No limitation is therefore intended except for those set forth in the claims which follow.

The invention having now been fully described, what is believed to be new, and what it is desired to secure by Letters Patent is:

1. An amusement device comprising a plurality of substantially horizontal trackways of generally channel shape having sides disposed in parallel relation at different elevations, a number of inclined trackways equal in number to said horizontal trackways and each communicating respectively with one of said horizontal trackways,

said inclined trackways being also of generally channel shape, a number of gate elements equal to the number of said trackways, one of said gate elements being disposed respectively in each of said inclined trackways, all of said gate elements being connected to a common member, whereby upon actuation of said common member all of said gate elements are actuated simultaneously.

2. A device according to claim 1, in which one side at least of the channels constituting said horizontal trackways is of transparent material.

3. A device according to claim 1 in which said horizontal trackways are disposed in stepped relation defined by steps and risers whereby the 15 riser between adjacent trackways constitutes a side guide for the lower of said adjacent trackways.

4. A device according to claim 3, in which there is secured to each riser a transparent plate to 20 constitute a side guide for the trackway next above.

5. A device according to claim 4, in which all of said gate elements are secured to a common rod, upon rotation of which all of said gate elements are simultaneously actuated.

6. A device according to claim 1, in which said horizontal trackways are disposed one above the other, and in which one side at least of the channels constituting said trackways is of transparent material.

7. A device according to claim 6, in which each of said gate elements is pivotally mounted in its respective inclined trackway, and in which a common actuating member is connected to each of said pivotal mountings to actuate all of said gate elements simultaneously.

8. A device according to claim 7, in which a crank is secured to the pivotal mounting of each of said gate elements, and in which all of said cranks are pivoted to a single actuating link.

AMBROSE W. GROH.
